UNITED STATES PATENT OFFICE.

ANGUS MACARTHUR, OF CHICAGO, ILLINOIS, ASSIGNOR TO THE KOPPERS COMPANY, OF PITTSBURGH, PENNSYLVANIA, A CORPORATION OF PENNSYLVANIA.

ALARM MECHANISM FOR REGENERATIVE REVERSAL SYSTEMS.

Application filed November 1, 1923. Serial No. 672,222.

The object of this invention is to provide an efficient and reliable mechanism for giving an alarm in case of a failure of the reversal machinery of regenerative heating 5 furnaces to function properly at the period when it should operate to reverse the flow of the heating gases.

In addition to the general object recited above, the invention has for other objects 10 such other improvements or advantages in construction and operation as are found to obtain in the structures and devices hereinafter described or claimed.

In the accompanying drawings forming 15 a part of this specification and showing for purpose of exemplification, a preferred form and manner in which the invention may be embodied and practiced, but without limiting the claimed invention to such illustrative instance or instances:

Figure 1 is a diagrammatic view illustrating an application of the alarm mechanism of the invention to a reversal mechanism for regenerative heating furnaces, such 25 as regenerative coke oven reversing mechanism;

Fig. 2 is an enlarged view of the alarm and immediate connections for operating the same;

Fig. 3 is an enlarged sectional view of the means for timing and controlling the flow of the operating fluid; and

Fig. 4 is an enlarged sectional view of the filter trap for the operating fluid.

The same characters of reference designate the same parts in each of the several views of the drawings.

In its present embodiment, the invention is incorporated in a reversing mechanism for coking plants of the well known Koppers regenerative type. For convenience, the present description will be confined to this embodiment and use of the invention; it will be understood, however, that the invention 40 is readily susceptible of other valuable applications, for example, reversing systems for regenerative heating furnaces generally, and that the invention is not confined in scope to the specific use and specific embodiment herein described as an illustrative example.

In the operation of a regenerative coke oven battery of the type above specified, the several heating flues are divided into inflow and outflow groups, with groups of

regenerators corresponding respectively to the inflow and outflow groups of flues. During the operating period between each reversal, the inflow group of flues and corresponding regenerators are supplied with 60 fuel gas and combustion supporting air for the purpose of flame propagation in the inflow flues. In one method of operation, some of the regenerators feed air to the inflow flues and others the fuel gas, this method being known as "gas oven" operation; in another method all of the inflow regenerators feed air to the flues, and the fuel gas is fed directly to the flues from supply mains, this latter method being known as 70 "coke oven" operation. Whatever method of flame propagation be employed in the regenerative heating system, it is essential that a reversal in flow of the heating gases be effected at the end of an operating period such as above described, so that the outflow flues and regenerators which operated during a previous operating period to convey waste gases to an exhaust main or stack flue be switched to the "inflow" function and also that, during the same reversal, the previous inflow-operating regenerators and flues be switched to the "outflow" function. This reversing operation is accomplished in such regenerative heating structures by reversing machinery which is timed to effect the change in function between inflow and outflow regenerators and flues at the end of each operating period.

The reversing mechanism includes in its 90 construction a pair of reversing cables 11 and 12 (see Fig. 1), one cable 11 of which controls and operates the various valves appertaining to one group of flues and regenerators and the other cable 12 the various 95 valves appertaining to the other group of flues and regenerators. In Fig. 1, there is shown a series of valves 13 for a group I of regenerators and flues and a series of valves 14 for a group O of regenerators and flues. For the sake of simplicity only one series of valves for each group of regenerators and flues is shown, but it will be understood that all other valves essential to effect the reversing operation will be included in the mechanism of which the cables 11 and 12 constitute part of the operating means. As shown in Fig. 1, the parts occupy the relative positions which they assume during an operative period and that 100 105 110

- part of the diagram designated by the reference character I represents the group of inflow flues and regenerators with the series of valves 13 open, whereas that part of the diagram designated by the reference character O represents the outflow flues and regenerators with the series of valves 14 closed to prevent supply of air or fuel gas to the outflow regenerators and flues.
- 10 At the end of the operating period, reversal is effected, according to the usual practice, by first shutting off the valves controlling the flow of fuel gas and air into the inflow regenerators and flues before 15 opening up the valves controlling the supply of fuel gas and air to the previous outflow regenerators and flues. This slight interval between the closing of the valves of the previous inflow regenerators and flues and 20 the opening of the valves of the previous outflow regenerators and flues is employed for the purpose of permitting a decarbonizing operation well understood in the art and described, for example, in prior 25 Letters Patent of Joseph van Ackeren No. 1,410,783 dated March 28, 1922, to take place in the previous inflow flues and regenerators. Consequently the reversing cable 11 is shifted toward the right to close the series 30 of valves 13 and such other valves as may be necessary before the reversing cable 12 is shifted toward the right to open the series of valves 14 and other valves appertaining to the group of flues and regenerators O to 35 give the inflow function to said latter group. The above described mode of operation of the reversing system during each reversal period is advantageously employed in the application thereto of the alarm mechanism 40 of the present invention.
- In its preferred embodiment in plants of this character, the alarm is preferably constituted of a whistle 15 for which steam is supplied by a steam pipe 16 through a controlling valve 17 operated by a valve stem 18, which when depressed opens the valve 17 to permit a flow of steam through the line 16 to blow the whistle 15. The operation of the stem 18 is controlled by a bell 45 crank lever 19 pivoted at 20 on a supporting bracket 21 mounted on the valve 17. The vertical arm 22 of the bell crank lever 19 is provided with a counterweight 23 and the horizontal arm 24 of said lever is bifurcated 50 as shown at 25 to receive the valve operating rod 26. Movement of the bell crank lever 19 toward the right, as shown in Fig. 2, is limited by a stop constituted of an upright 55 27 secured to the main 16.
- 60 The valve operating rod 26 is provided with an operating lug 28 which, when the rod 26 is lifted the required distance engages the arm 24 of the bell crank lever and in lifting said arm 24 forces the bell crank lever 19 toward the left so that the counter-

weight 23 of said lever will cause the vertical arm 22 to move downwardly toward the left and in so doing bring the operating face 29 into engagement with the valve plunger 18 to depress the latter, open the 70 valve 17 and permit steam to flow through the line 16 to blow the whistle 17.

The movement of the valve operating rod 26 is controlled by a float 30 to which the lower end of said rod 26 is secured. The 75 float 30 may be raised and lowered in a float chamber 31 formed by a surrounding casing 32 and through the top of which the valve operating rod 26 passes, as shown more particularly in Fig. 2. Preferably, the rod 26 80 as well as the float 30 are guided in their movement by bearings 33 and 34 encircling the rod 26 and secured to brackets 35 and 36 respectively mounted on the top and bottom of the surrounding casing 32.

The raising of the float 30 is caused by an operating fluid such as water supplied to the bottom of the float chamber by a pipe 37 from a supply tank 38. The supply tank 38 communicates with a supply pipe 39 and the latter is connected by a by-pass 40 having a controlling valve 41 with a pipe 42 which extends to a manually operated valve 43. The valve 43 is connected by a short pipe union 44 with the controlling valve 45 of 95 the alarm mechanism and said valve 45 is in turn connected with the supply pipe 37. At the point where the by-pass 40 connects with the pipe 42, there is preferably provided, as shown in Fig. 4, a wire cloth filter 100 46 enclosed in the pipe 42 and removable for cleaning purposes by unscrewing a cap or plug 47 which normally closes the lower end of the pipe 42. A second by-pass 48 located above the by-pass 40 connects the 105 pipe 39 with the pipe 42 and the valve 49 controlling the flow through the by-pass 48 may be opened when valve 41 of by-pass 40 is closed during an operation of cleaning out the wire filter 46 in the bottom of the pipe 110 42. The last mentioned construction permits an uninterrupted operation of the system even during cleaning out of the filter.

As shown in Fig. 3, the pipe 42 is made in two sections for the purpose of interposing in the fluid line a disk 50 having a restricted aperture 51 which regulates and controls the flow of fluid into the pipe 37. The two sections of the pipe 42 and the disk 50 are united by means of pipe union 52. During the operating period between reversals and valve 49 is normally closed, the valve 41 is open, as well as valve 43 and the alarm control valve 45. The alarm control valve 45 is a three-way valve controlling 125 the flow through the pipe 44, pipe 37, and a drain pipe 53 all of which are connected to the valve 45, as shown in Fig. 1 and is controlled in its operation by a lever 54 having a weight 55 which tends to throw the lever 130

- to operate the valve 45 to permit a flow of the fluid from the source of supply 38 into the pipe 37 and float chamber 31. The flow of the fluid is controlled by the apertured 5 plug 50 hereinbefore described, so that during the operating period between reversals, while the valve 45 is open to permit flow through the line 37, the quantity discharged into the flow chamber 31 is restricted to an 10 amount requiring a period of time in excess of the normal operating period between reversals to cause the float 30 to be elevated a distance sufficient to throw the lever 19 into position for operating the whistle 15. 15 Secured to the lever 54 is a flexible connection 57, the upper end of which is secured at 58 to a sheave 59 around which passes a cable 60. The opposite ends of the cable 60 are guided by fixed pulleys 61 and are secured respectively to the reversing cables 20 11 and 12. Whenever one group of flues and regenerators, such as the group I, is in open position, while the other group of flues and regenerators is in closed position, such as the 25 group O, as shown in Fig. 1, which happens during a period between reversals, the sheave 59 is lowered by the cable 60 to permit the counterweight 55 to move the controlling valve 45 to "filling" position, so that 30 a supply of fluid is permitted to flow into the float chamber 31. At the end of the operating period between reversals, the reversing cable whose valves were in open position should be operated, as hereinbefore 35 stated, to close the valves before the other cable is operated to open the valves of the previous outflow flues and regenerators. Assuming this to be the cable 11, the operation of moving the cable 11 to the right to close 40 the valves 13, would draw up the sheave 59 and with it the lever 54 to throw the valve 45 so that the pipe 37 would be connected with the drain pipe 53. The result would be 45 that the float would be permitted to fall in the float chamber 31 and the alarm would not be sounded. As soon as the reversal is completed, for example, by moving the cable 12 toward the right to open the valves 14 to cause the regenerators and flues controlled 50 thereby to become inflow regenerators and flues, the sheave 59 would be again lowered to re-establish a supply of fluid to the float chamber 31. During normal operating conditions, the above described draining of the 55 float chamber would happen at each reversal to prevent blowing of the whistle 15. If, however, the reversal machinery should fail during a reversal period, for example, should a reversing cable such as the 60 cable 11 fail to move toward the right to close the valves at the beginning of the reversing period, the sheave 59 would remain in lowered position and the supply of fluid would be continued into the float chamber 31. Consequently, the float would continue 65 to rise and the further upward movement of the rod 26 would throw over the bell crank lever 19 toward the left to operate the whistle 15. This operation would also happen in case of a failure of the other reversing cable 70 12 to close the valves at the end of another operating period. 75 The invention as hereinabove set forth may be variously embodied within the scope of the claims hereinafter made. 75
- I claim:
1. In combination with a pair of reversing cables; a whistle; a float chamber; a float therein movable to a predetermined position for effecting the operation of the whistle; an operating-fluid supply line; a drain; a controlling valve for connecting either the drain with the float chamber or the float chamber with said operating-fluid supply line; connections between both reversing cables and said controlling valve, operable when both cables are in "closed" position to throw the controlling valve to "draining" position, but when either one of them is in "open" position to throw said valve to connect the float chamber with the operating-fluid supply; and means for regulating the supply of operating fluid to the float chamber whereby an interval greater than the normal interval between reversals is required for the float to reach its whistle-operating position substantially as specified. 80 90 95
  2. In combination with a pair of reversing cables; an alarm; a float chamber; a float therein movable to a predetermined position for effecting the operation of the alarm; an operating-fluid supply line; a drain; a controlling valve for connecting either the drain with the float chamber or the float chamber with said operating-fluid supply line; connections between both reversing cables and said controlling valve, operable when both cables are in "closed" position to throw the controlling valve to "draining" position, but when either one of them is in "open" position to throw said valve to connect the float chamber with the operating-fluid supply; and means for regulating the supply of operating fluid to the float chamber whereby an interval greater than the normal interval between reversals is required for the float to reach its alarm-operating position substantially as specified. 100 105 110 115
  3. In combination with a pair of reversing cables, an alarm; instrumentalities comprising means movable to a predetermined position for effecting the operation of the alarm; means for regulating the power for the alarm operating instrumentalities comprising means whereby an interval greater than the normal interval between reversals is required for the alarm to operate; and connections between the reversing cables and said instrumentalities comprising means for effecting operation of 120 125 130

the alarm for rendering the latter inoperative by the proper functioning of the reversing cables during reversal substantially as specified.

5 4. In combination with a reversing mechanism, an alarm; instrumentalities comprising means movable to a predetermined position for effecting the operation of the alarm; means for regulating the power for the 10 alarm operating instrumentalities comprising means whereby an interval greater than the normal interval between reversals is required for the alarm to operate; and connections between the reversing mechanism and 15 said instrumentalities comprising means for effecting operation of the alarm for rendering the latter inoperative by the proper functioning of the reversing mechanism during reversal substantially as specified.

20 5. In combination with a pair of periodically operable regenerative reversing cables: an alarm; fluid pressure operated timed means adapted for effecting the operation of said alarm upon failure of either of said 25 reversing cables to function after the normal interval of time between reversals; timing means adapted for effecting timed operation of said timed means by fluid pressure; and resetting means adapted to be operated by 30 the reversing cables and to effect, when operated by said cables upon the proper functioning of both of them at the end of the normal interval of time between reversals, a resetting of said timed means for another 35 timed operation by said timing means before said timed means effects the operation of said alarm.

6. In combination with a pair of periodically operable regenerative reversing cables: 40 an audible alarm; timed means adapted for effecting the operation of said audible alarm upon the failure of either of said reversing cables to function after the normal interval of time between reversals; timing means 45 adapted for effecting timed operation of said timed means; and resetting means adapted to be operated by the reversing cables and to effect, when operated by said cables upon the proper functioning of both of them at the 50 end of the normal period of time between reversals, a resetting of said timed means for another timed operation by said timing

means before said timed means effects the operation of said audible alarm.

7. In combination with a periodically operable regenerative reversing mechanism: an alarm; timed means adapted for effecting the operation of said alarm upon the failure of said reversing mechanism to function after the normal interval of time between 55 reversals; timing means adapted to effect timed operation of said timed means; and resetting means adapted to be operated by the reversing mechanism and to effect, when operated by the reversing mechanism upon 60 the proper functioning thereof at the end of the normal period between reversals, a resetting of said timed means for another 65 timed operation by said timing means before said timed means effects the operation of 70 said alarm.

8. In combination with a periodically operable regenerative reversing mechanism: an audible alarm; timed means adapted for effecting the operation of said alarm upon 75 the failure of said reversing mechanism to function after the normal interval of time between reversals; timing means adapted to effect timed operation of said timed means; and resetting means adapted to be operated 80 by the reversing mechanism and to effect, when operated by the reversing mechanism upon the proper functioning thereof at the end of the normal period between reversals, a resetting of said timed means for another 85 timed operation by said timing means before said timed means effects the operation of 90 said audible alarm.

9. In combination with a periodically operable reversing mechanism: an alarm; 90 timed means adapted for effecting the operation of said alarm upon the failure of said reversing mechanism to function after the normal interval of time between reversals; timing means adapted to effect timed operation of said timed means; and means operable by the reversing mechanism upon the proper functioning thereof to effect another 95 timed operation of said timed means by said timing means.

In testimony whereof I have hereunto set my hand.

ANGUS MACARTHUR
